UNITED STATES PATENT OFFICE

JAMES P. MAUZEY, OF KENNEWICK, WASHINGTON

AIR-HEATING MEANS

Application filed January 7, 1930. Serial No. 419,011.

This invention relates to air heating means, more particularly adapted to heating large quantities of air, and has as one of its objects to provide an air heating means that will utilize the waste heated gases of chimneys to heat the air.

Another object of the invention is to provide an air heating means that by its arrangement in the chimney will deflect the heated gases to the next superimposed section thereby providing great efficiency;

A further object of the invention is to provide an air heating means that will adapt the ornamentations of the chimney to provide a reservoir to arrest the flow of air and afford a certain preheating effect thereto;

A further object of the invention is to provide an air heating means, contained within a chimney, that may be readily cleaned.

With these and other objects in view reference is now made to the accompanying drawings in which

Fig. 1 is a side elevation of a power plant chimney, partly in section showing the disposition of one form of my device;

Fig. 2 is a cross section thereof taken on the line 2—2 of Fig. 1;

Fig. 3 is a cross section of my preferred form of device, taken on the line 3—3 of Fig. 4;

Fig. 4 is a side elevation of my preferred form with part broken away;

Fig. 5 is a side elevation thereof, with part broken away to show the course of the air; and

Fig. 6 is a sectional elevation showing an arrangement of conductors providing for deflecting the heated gases from one section to another.

Having reference to the drawings like numerals refer to like parts throughout the several views, and the numeral 1 refers to a chimney of the customary form, and constructed of the usual material, such as brick, as represented in Fig. 1, or other materials adapted for the purpose.

The illustration in Fig. 1 represents a chimney of the larger type as used to remove gases from the boilers of a power plant and the remaining figures also represent chimneys

of the larger type and while the representations are typical it must be understood that the device is applicable to smaller chimneys such as are used in residences or the like.

Where the chimney is adapted for use in connection with boilers, the discharge from the boilers may enter through the orifices 2 shown in Fig. 1, and like orifices (not shown) obviously may be used with other forms of chimneys.

As it is a common practice for ornamentation to provide a moulding 3 around the top of the chimney, this moulding is taken advantage of and is constructed hollow to provide a reservoir 4, which by its size with relation to the chimney proper will arrest a flow of air entering and passing out therefrom through pipes having less area in cross section, and as the wall 5 of the chimney opposite this reservoir will be warmed from the flue gases, the reservoir will provide a pre-heater for air therein.

Connected into this reservoir are air conductors 6 which may be of various types as shown, the essential features thereof however consisting of receiving the air at the upper part of the chimney and forcing it downward to the discharge end at the lower part of the chimney, and at the same time to shape and position the conductors therein at an angle to the path of the upflowing heat for a purpose to be explained.

With this in mind a coil 7 is used, as shown in Fig. 1, in which case the deflection from the horizontal of each convolution will provide sections 8 positioned in a staggered relation that will intercept and deflect the upflowing gases from one section to the other.

In Fig. 6 is shown a modification of this form wherein the sections 8 of the air conductor are zigzagged in their downward path for the same purpose of interception and deflection.

While these views show a continuous conductor 6 passing from the relatively cooler upper part 9 of the chimney to the relatively hotter lower part 10 thereof, in my preferred form I use transversely positioned pipes for the conductor sections 8, and while the cross section of pipe being circular is well adapted

to deflect the heated gases I prefer and provide in my transversely positioned conductors a section of diamond or like cross section (see Fig. 4) to offer as little resistance as possible to the up-flow of gases. And to obtain greater efficiency from the transversely positioned pipes I arrange these pipes in staggered relation, as before mentioned, so that the heat deflected from one row, or section, of pipes will encounter the next upper row in its passage through the chimney.

These pipes are likewise formed to constitute sections 8 but differ from the continuous conductors mentioned in that they consist of separate pipes imbedded in the walls of the chimney in a manner to provide a passageway for the air from outside to outside of the chimney wall.

With this arrangement the reservoir 4 will be preferably constructed of an insulated material, for economical reasons, although there is no objection to construction as in that shown and described for Fig. 1.

In addition a cover 11 is constructed which surrounds the chimney, and this cover is separated into compartments 12 by oppositely positioned partitions 13 as shown in Fig. 5, which partitions will direct the air from the uppermost section to the next lower section, when it will pass through the chimney into an opposite compartment 12 having a like partition 13 through which compartment it will continue downward to the next lower section to again pass through the chimney, and continuing in a like manner finally arrive at its point of discharge after repeatedly passing through the chimney and subjected to the heat of the gases.

To supply this reservoir with air a blower 14 or other means is utilized which consists preferably of a motor 15 and fan 16, the fan being encased in a housing 17 with the housing in turn being connected with a suction pipe 18 adapted to supply the air to said blower, and feed pipes 19 will be connected to this housing and extend therefrom to the reservoir 4 to supply that member.

The supply may be conducted to the reservoir either outside the chimney as shown in Fig. 1 and Fig. 6, or may be extended up through the chimney as shown in Figs. 4 and 5. The latter case is deemed preferable as with the air rising through these pipes within the heated gases a more even temperature is provided than when going up the outside, due to the possible effect of climatic conditions.

As the air conductors are provided with a continuous passage to the point of distribution it is obvious that the blower may be utilized to continue the movement of the air to their destinations.

If it is desired to have a heat of slightly lower temperature than that created in the

air conductors, a vertical pipe 20 may be connected with the reservoir 4 and extend downward in a straight line to be conducted to its point of discharge in a like manner to that of the conductor and these may be utilized in combination with the air conductors if desired as they will absorb less heat in proportion to their relative lengths.

In either event by forcing the air through the conductor 6, and by providing a continuous passageway, the air is forced downward against the effect of rarefaction and by its rarefaction its velocity will be increased, which increase in velocity will compensate for any losses which might occur by an unanticipated leakage in the pipes.

In use, and assuming that the heated gases are rising in the chimney, the blower 14 will be started, when air will be drawn in through the suction pipe 18 to pass through the housing 17 of the blower with a velocity created by the fan 16 therein, to discharge with the same velocity into the reservoir, which reservoir, due to its larger area, will provide for a decrease in velocity, when the air will enter the conductors 6 and from then on assume the initial velocity, or an increased velocity due to rarefaction, and the expansion due to that rarefaction. The air will then travel through the passageway of the conductors to its exit for final use.

Having thus described my invention, I claim—

1. In an air heating means, the combination with a chimney, of a distributing reservoir formed as a moulding for said chimney, air conductors connected with said reservoir and disposed within said chimney and adapted to conduct air from the relatively cooler part of said chimney to the relatively hotter part thereof, and means to supply air to said reservoir and to move said air in said conductors against the effect of rarefaction, and utilizing said means to continue its movement to effect the proper distribution of the air.

2. In an air heating means, the combination with a chimney, of a distributing reservoir formed as a moulding for said chimney, air conductors connected with said reservoir and disposed within said chimney and adapted to conduct air from the relatively cooler part of said chimney to the relatively hotter part thereof, and disposed therein at an angle to the path of the upflowing heat, and means to supply air to said reservoir and to move said air in said conductors against the effect of rarefaction, and utilizing said means to continue its movement to effect the proper distribution of the air.

3. In an air heating means, the combination with a chimney, of a distributing reservoir formed as a moulding for said chimney, air conductors connected with said reservoir and disposed within said chimney and adapted to conduct air from the relatively cooler part of

5 said chimney to the relatively hotter part thereof, and disposed therein at an angle to the path of the upflowing heat and in a manner to deflect the heat from one section of the air conductors to another, and means to supply air to said reservoir and to move said air in said conductors against the effect of rarefaction, and utilizing said means to continue its movement to effect the proper distribution 10 of the air.

10 4. In an air heating means, the combination with a chimney, of a distributing reservoir formed as a moulding for said chimney, of air conductors having sections thereof disposed in zigzag relation within said chimney and adapted to conduct air from the relatively cooler part of said chimney to the relatively hotter part thereof and disposed therein at an angle to the path of the 15 upflowing heat and in a manner to deflect the heat from one section of the air conductors to another, and means to supply air to said reservoir and to move said air in said conductors against the effect of rarefaction, and 20 utilizing said means to continue its movement to effect the proper distribution of the air.

20 5. In an air heating means, the combination with a chimney, of a distributing reservoir formed as a moulding for said chimney, of air conductors having sections thereof disposed in staggered relation in said chimney and adapted to conduct air from the relatively cooler part of said chimney to the relatively hotter part thereof and shaped and positioned in said chimney to intercept and to deflect the upflowing heat from one section of the air conductors to the other, and means to supply air to said reservoir and to move said air in said conductors against the effect of rarefaction, and utilizing said means to continue its movement to effect the proper distribution of the air.

30 6. In an air heating means, the combination with a chimney, of a distributing reservoir formed as a moulding for said chimney, of transversely positioned air conductors having sections thereof positioned in staggered relation, and mounted in said chimney, and having a cross section adapted to deflect the upflowing heat to each succeeding section, means surrounding said chimney to direct the air from one section to the other in a manner to conduct air from the relatively 35 cooler part of said chimney to the relatively hotter part thereof, and means to supply air to said reservoir and to move said air in said conductors against the effect of rarefaction, and utilizing said means to continue its movement to effect the proper distribution of the air.

40 7. In an air heating means, the combination with a chimney, of a distributing reservoir formed as a moulding for said chimney, and disposed to provide a pre-heater

45 for air, of transversely positioned air conductors having sections thereof positioned in staggered relation, and mounted in said chimney, and having a cross section adapted to deflect the upflowing heat to each succeeding section, a cover means surrounding said chimney and provided with partitions, to direct the air from one section to the other in a manner to conduct air from the relatively 50 cooler part of said chimney to the relatively hotter part thereof, and means to supply air to said reservoir and to move said air in said conductors against the effect of rarefaction, and utilizing said means to continue its movement to effect the proper distribution of the air.

55 In testimony whereof I have affixed my signature.
